UNITED STATES PATENT OFFICE.

FRANK E. WHITNEY, OF MELROSE, MASSACHUSETTS.

PRESSURE-EQUALIZER.

No. 852,150.

Specification of Letters Patent.

Patented April 30, 1907.

Application filed January 11, 1907. Serial No. 351,770.

To all whom it may concern:

Be it known that I, FRANK E. WHITNEY, a citizen of the United States, and a resident of Melrose, in the county of Middlesex and 5 Commonwealth of Massachusetts, have invented certain new and useful Improvements in Pressure-Equalizers, of which the following is a full, clear, and exact description.

In the operation of gas engines, it is customary to introduce a rubber bag as a section of the conduit through which the gas is fed to the engine, for the purpose of equalizing the pressure of the main thereto.

The object of this invention is the construction of an improved means by which to suitably regulate or equalize the gas pressure without the possibility of vitiating the surrounding air, and without the danger of fire and explosions.

20 A further object of my invention is the preservation and lengthening of the period of usefulness of which the expansive-medium shall be capable and the simplifying and cheapening of the device.

25 Referring to the drawings forming part of this specification, Figure 1 is a sectional elevation of a building containing a gas engine provided with my improved pressure equalizer in its simplest form. Fig. 2 is a central 30 sectional elevation of my pressure equalizer in its preferred construction. Fig. 3 is a side elevation of the same.

The gas engine 1, which is shown as located within a building 2, is supplied with 35 gas through a pipe 3; and formed as a portion of said pipe is the equalizer 10. In its simplest form, this equalizer comprises an approximately semi-spherical chamber 11^a; a rubber diaphragm 12, and a curved guard 40 13; both the guard and chamber being formed with suitable flanges 14 between which to clamp the edge of said diaphragm. From the space inclosed between said guard and diaphragm opens a pipe 15 extending 45 through to some point exterior to said building; such point as illustrated in Fig. 1 being the roof.

As the gas flows through the chamber 11 on its way to the engine, its pressure forces 50 the diaphragm to expand to a greater or less extent; and this expansion is increased or diminished in accordance with the fluctuations caused in such pressure by the intermittent actuations of the engine. Should, 55 now, any slight perforation form through the diaphragm 12, the gas escaping through the

same passes into the space between the guard and diaphragm, and thence through the pipe 15 to the atmosphere without the structure. Further, should through any imperfections 60 in manufacture, the diaphragm tear wholly through, the outpouring gas would simply pass through the pipe 15 outside the building and do no harm. The pipe 15 being substantially smaller than the conduit 3, only 65 enough gas would flow through the former to indicate something was wrong by a slowing down of the engine, but not necessarily to wholly stop it. In case the nature of the work being performed by the engine pre- 70 cluded a stoppage for repairs, the valve 16 in the pipe 15 is closed, and the engine enabled to continue its operation. As soon as closing time arrived, the gas can be shut off from the pipe 3; the guard 13 unbolted; the old dia- 75 phragm removed, and a new one substituted. Then the valve 16 can be opened, the gas turned on, and the engine is ready for its task.

My preferred construction, that shown in 80 Figs. 2 and 3, consists simply in having the chamber 11 cylindrical, with a diaphragm 12 and guard 13 at both top and bottom, and the pipe 15 formed with branches opening into both guard-spaces. By thus doubling 85 the area of the diaphragm, the entire device may be made smaller for the same degree of equalizing capacity. Another advantage consists in the fact that should either dia- 90 phragm rupture, the particular valve 16 or 95 16' belonging thereto can be closed, and the other diaphragm perform the work until opportunity for repairs arrives.

By having the curvature of the guards 13 such that only the maximum pressure liable to 95 occur in the gas-main is capable of expanding the diaphragms into contact therewith, such diaphragms are effectually prevented from receiving any excessive strains should such ordinarily maximum pressure be for any cause suddenly exceeded. Hence the dia- phragms are shielded against rupture from such cause.

I have found it an exceedingly expensive matter to manufacture, and also to fit in place, the spherical gas bags now in use for the purpose of equalizing the pressure to the engine. The plane rubber diaphragms which I use in my invention are, on the contrary not only comparatively inexpensive to manufacture, being cut from cheap sheet rubber, but they are easily and quickly applied to the cyl-

inder or chamber 11. Further, when the gas is shut off from the gas bags above referred to, they collapse upon themselves, the contacting surfaces adhere more or less strongly, and 5 then when suddenly expanded by the gas being turned on, the adhering surfaces are ripped apart with an abruptness which always causes injury, and soon brings about weakness and even destruction. It is evident that the tarry matter carried by the gas in suspension will be deposited with especial thickness upon the lower surfaces of the said gas bag, and soon deteriorate and weaken the same. In my construction, that shown 10 in Fig. 1, the rubber diaphragm composes the roof of the pressure equalizer, and the indestructible cast iron the floor thereof. Consequently, all such tarry deposits can do no damage to my invention. Moreover, a spherical rubber bag when once expanded cannot 15 so readily yield to differences in pressure as can a flat rubber diaphragm such as I employ. Hence, by using a comparatively heavy grade of rubber, a sufficiently strong resistance to pressure is given, together with a marked extent of yielding to variations in 20 such pressure.

What I claim as my invention and for which I desire Letters Patent is as follows, to wit:—

25 1. A pressure equalizer comprising a metal chamber having one side open, a sheet of rub-

ber covering said open side, and means delivering gas to and from said chamber.

2. A pressure equalizer comprising a metal chamber having its upper side open, a sheet 35 of rubber covering said side, and means delivering gas to and from said chamber.

3. A pressure equalizer comprising a cast iron chamber having an open flanged side, a metal guard disposed to be bolted tightly 40 upon said flange, and a sheet rubber diaphragm clamped at its edges between said flange and guard; said guard being provided with a pipe communicating with the atmosphere, and said chamber being adapted to 45 have gas delivered to and from it.

4. A pressure equalizer comprising a cylindrical metal chamber constituting a section of a gas engine supply conduit, sheet rubber diaphragms forming opposite walls of said 50 chamber, guards inclosing said diaphragms, a pipe terminating in communication with the atmosphere, and valved tubular branches joining said pipe to the spaces between said guards and diaphragms.

55 In testimony that I claim the foregoing invention, I have hereunto set my hand this 9th day of January, 1907.

FRANK E. WHITNEY.
